(57) **CLAIM**

The ornamental design for a display screen with graphical user interface having a three-dimensional appearance, as shown and described.

DESCRIPTION

FIG. 1 is a front view of a display screen with graphical user interface having a three-dimensional appearance showing the claimed design;

FIG. 2 is another front view thereof, showing the rear orientation of the graphical user interface;

FIG. 3 is another front view thereof, showing the left side orientation of the graphical user interface;

FIG. 4 is another front view thereof, showing the right side orientation of the graphical user interface;

FIG. 5 is another front view thereof, showing the top orientation of the graphical user interface; and,

FIG. 6 is another front view thereof, showing the bottom orientation of the graphical user interface.

The outer broken lines in the figures show a display screen or portion thereof and form no part of the claimed design. The graphical user interface in FIGS. 1 to 6 is shown in various orientations to provide an understanding of the three-dimensional appearance of the design.
